UNITED STATES PATENT OFFICE

PERCY W. STEPHENS, OF CHICAGO, ILLINOIS

FOUNTAIN BRUSH

Application filed November 17, 1928. Serial No. 320,022.

This invention relates to improvements in fountain brushes, and more particularly to brushes of the type adapted to replace threaded caps of liquid-containing bottles or cans.

The principal object of the invention is to provide a simple and inexpensive construction of devices of the character described including a valve, whereby the base 10 of such devices may be formed or cast in one piece, and the entire device be made relatively light, strong and durable, yet especially economical in construction.

The invention may best be understood by reference to the accompanying drawings, in which

Figure 1 is a view showing a bottle to which one form of my improved attachment is applied, with the attachment shown in vertical section.

Figure 2 is an enlarged vertical section of a modified form of my improved attachment, and

Figure 3 is a vertical section of another modified form of my invention.

Referring to details of the form shown in Figure 1, my improved attachment is indicated generally at 10 and is adapted to be detachably connected to a bottle or similar liquid container 11 having a screw threaded neck 12. My attachment consists of a base portion 13, preferably circular in form, and a neck portion 14 provided with an interior threaded aperture 15 adapted to fit on the threaded neck 12 of the bottle or container 11. In the form shown, the body and neck portions 13 and 14 of the attachment are formed of an integral casting, preferably of bakelite or similar composition, with the threads in the neck moulded therein, as shown. The neck 14 is provided with a cross partition 16, having a hollow boss disposed centrally thereof extending downwardly so as to form an annular recess 18 on the underside of said partition, as shown.

Valve means for the attachment consist of a recess 24 formed in the upper face of the boss 17, and valve member 25 seated in an aperture 26 extending laterally through one side wall of said boss, so as to afford communication between the recess 24 and the annular recess 18

at the bottom of the body member. The valve member 25 has suitable control means extending to the exterior of the body, in the form shown said valve member being screw-threaded in the exterior wall of the neck 14 and 55 having a knurled head 27 at its outer end adapted to be turned by the fingers in order to open or close the valve.

A brush member is secured to the lower face of said body member by suitable means, 60 in the form shown in Fig. 1, said brush member comprising an annular metallic base plate 20 having bristle tufts 21 suitably secured therein, as for instance by wiring the same in the usual manner. The metal plate 20 is 65 provided with apertures 22 in which the ends of the bristle tufts are set, which apertures also afford egress of liquid when the attachment is in use.

The annular plate 20 carrying the brush 70 is attached to the base by providing an annular overhanging shoulder 28 on the bottom of the body, under which shoulder the edge of the plate is closely fitted, as by springing said plate into place.

In the form shown in Figure 2, a similar construction is utilized excepting that in this form the brush member consists of a wooden or composition base 20^a which is secured to the body by means of a circular metallic ring 80 28^a closely fitting against the adjacent margins of the attachment base and brush base members 13 and 20^a, and having its upper and lower edges 29, 29^a flanged inwardly as by upsetting the same so as to secure the two 85 members together.

In the modified form shown in Figure 3, the brush base is secured to the body by means of an elongated securing member herein consisting of a bolt 30 which is passed through the centrally disposed boss 17^a into securing engagement with the central portion of the brush base 20^b, as shown. Manifestly, a screw may also be used in this place, with the threads engaging the brush base 20^b, if desired. In this form the recess or passage 24^a in said boss communicating with the valve opening 26 is offset laterally from the center of the boss in order to accommodate the attaching bolt 30; but construction of the valve 100

including valve member 25 is otherwise the same as shown in the forms heretofore described.

Among the advantages of the general structure above described is the design of the body member of the attachment which makes it particularly adapted for moulding in a single piece. The central boss 17 is so arranged as to provide a particularly simple valve construction whereby the screw threaded valve member 25 or its equivalent can be inserted through the side of the neck in alignment with the passage 26 formed through the side wall of the boss. The arrangement of passage and valve greatly simplifies the machining of the piece, and eliminates the use of expensive inserts and other metallic parts, which might otherwise be necessary in order to provide a suitable valve to control the flow of fluid to the brush.

The attaching means shown in Figure 3 is especially advantageous owing to its simplicity of construction, wherein the head of the bolt 30, or an equivalent screw, as described, 25 being accessible through the threaded attaching aperture 15 so as to provide especially simple and labor-saving means for attaching the brush to the body of my device.

I claim as my invention:

30 1. An attachment for liquid containers comprising a brush, and an integral moulded annular body having a threaded attachment opening, a cross partition including an offset longitudinal portion having a passage there- 35 through opening toward one side wall of said body, and a valve member threaded in said side wall in endwise alignment with said opening, and adapted to close the same.

40 2. In an attachment for liquid containers, a brush, and a body comprising an attaching neck and a base for a brush, a cross partition in said neck having a boss thereon, and a passage therethrough and into said boss and having a passageway opening to one side thereof, and valve means extending through 45 the side wall of said body and adapted to close said passage.

50 3. In an applicator attachment for liquid containers, a body member having an integrally threaded attaching neck and a base for a brush, a cross partition in said neck having an axially projecting boss and a passage therethrough and into said boss, and said boss having a passage opening to one side thereof, valve means for closing said passage comprising a stem threaded in and extending through one side of said neck, and a perforated brush attached to said base.

60 4. In an attachment for liquid containers, a body comprising an attaching neck and a base, a cross partition in said neck having a passageway therethrough opening toward one side wall of said neck, valve means extending through said side wall of said neck 65 and adapted to close said passage, a brush

member, and means extending through said partition for securing said brush member to said body.

Signed at Chicago, Ill., this 9th day of November, 1928.

PERCY W. STEPHENS.
